(57) **CLAIM**

The ornamental design for the pivoting curtain rod support, as shown and described.

DESCRIPTION

FIG. 1 is a front perspective view of a first embodiment of the pivoting curtain rod support.

FIG. 2 is a rear perspective view of a first embodiment of the pivoting curtain rod support.

FIG. 3 is a front elevation view of FIG. 1.

FIG. 4 is a rear elevation view of FIG. 1.

FIG. 5 is a left side elevation view of FIG. 1.

FIG. 6 is a right side elevation view of FIG. 1.

FIG. 7 is a top plan view of FIG. 1.

FIG. 8 is a bottom plan view of FIG. 1.

FIG. 9 is a front perspective view of a second embodiment of the pivoting curtain rod support.

FIG. 10 is a rear perspective view of a second embodiment of the pivoting curtain rod support.

FIG. 11 is a front elevation view of FIG. 9.

FIG. 12 is a rear elevation view of FIG. 9.

FIG. 13 is a left side elevation view of FIG. 9.

FIG. 14 is a right side elevation view of FIG. 9.

FIG. 15 is a top plan view of FIG. 9.

FIG. 16 is a section view taken along line 16—16 of FIG. 11 showing the top elevation of the rod support block; and,

FIG. 17 is a bottom plan view of FIG. 9.

The broken line showing of the opening for a curtain rod is for illustrative purposes only and forms no part of the claimed design.
